UNITED STATES PATENT OFFICE.

THOMAS B. CANN, OF WAKEFIELD, MASSACHUSETTS, ASSIGNOR TO THE HEYWOOD BROTHERS & WAKEFIELD COMPANY, OF SAME PLACE.

CAR-SEAT.

SPECIFICATION forming part of Letters Patent No. 657,480, dated September 4, 1900.

Application filed April 25, 1900. Serial No. 14,238. (No model.)

To all whom it may concern:

Be it known that I, THOMAS B. CANN, of Wakefield, in the county of Middlesex and State of Massachusetts, have invented certain new and useful Improvements in Car-Seats, of which the following is a specification.

This invention relates to a car-seat having a reversible or swinging back, a foot-rest frame which is reversible with the back, and a seat which is also reversible, in that its transverse inclination can be varied to raise that edge which is at the front and depress the edge which is at the rear.

The invention has for its object to provide simple and efficient means whereby the reversal of the back causes also a reversal of the position of the foot-rest frame and seat.

The invention consists in the improvements which I will now proceed to describe and claim.

Of the accompanying drawings, forming a part of this specification, Figure 1 represents a top plan view of a car-seat embodying my invention, the seat-cushion being removed. Fig. 2 represents a section on line 22 of Fig. 1.

The same reference characters indicate the same parts in both of the figures.

The rigid supporting-frame of the seat comprises the two end pieces 22 and the connecting-bars 33, the upper sides of the connecting-bars being inclined to form guides for the seat-supporting slides 44, the latter having inclines 55 on the under sides of their end portions, bearing on the inclined upper surfaces of the bars 33.

66 represent rock-shafts which are journaled in bearings on the end pieces 22 of the seat-frame. To said rock-shafts are affixed arms 77 and cams 88. The arms 77 are provided on their outer ends with studs 99, which enter slots 10, formed in the cross-bars 11 of the foot-rest frame, said frame comprising the arms 11, which are pivoted at 12 to the seat-frame, and the parallel foot-rests 1313, which are attached to and extend between the arms or cross-bars 11. The cams 88 bear against lugs 1414, formed on the seat-supporting slides 44. The arms 77 and cams 88 of one rock-shaft project at a different angle from the arms 77 and cams 88 of the other

rock-shaft, as shown in Fig. 2, the relative arrangement being such that when the arm and cam of one rock-shaft are raised the arm and cam of the other rock-shaft are depressed, thus causing the arms 77 to act conjointly in holding the cross-bars 11 of the foot-rest frame in an inclined position and the cams 88 to act conjointly in holding the seat-supporting slides 44 at one end of their 60 movement.

16 represents the seat-back, to the ends of which are affixed metal arms 17, the lower ends of which are provided with ears 1818. To said ears are jointed two parallel links 19 65 19, the lower ends of which are fixed rigidly to the rock-shafts 66.

The operation is as follows: When the seat-back is moved from one edge of the seat to the other, the swinging movement of the 70 links 19 causes a partial rotation of the rock-shafts 66, thus elevating the arms and cams of one rock-shaft and depressing the arms and cams of the other rock-shaft, the result being a reversal of the positions of the foot-rest frame and of the seat-supporting slides, 75 the forward edge of the seat-frame being raised and its rear edge depressed, while the foot-rest under the forward edge of the seat is raised out of the way and the foot-rest under the rear edge of the seat is depressed to an operative position.

My invention is not limited to the exact details of construction and arrangement of parts here shown, and the construction and 85 arrangement may be variously modified without departing from the spirit of the invention.

In Fig. 1 I have omitted one of the arms 77 from each shaft. 90

I claim—

1. In a car-seat, a fixed seat-frame, a foot-rest frame pivoted to the seat-frame below the seat and comprising cross-bars having slots, and foot-rests which are alternately elevated 95 and depressed by movements of the frame, two rock-shafts journaled in bearings in the seat-frame and each having two arms engaged with the slots in the cross-bars of the foot-rest frame, a reversible seat-back, and parallel links jointed to the back and attached rigidly to the rock-shafts, the arms of one

rock-shaft being so arranged relatively to the arms of the other rock-shaft that when the back is reversed the arms of one rock-shaft are depressed, while those of the other rock-shaft are raised, whereby a reversal of the position of the back causes a reversal of the position of the foot-rest frame, as set forth.

2. In a car-seat, a fixed seat-frame having seat-guiding inclines, a foot-rest frame pivoted to the seat-frame below the seat and comprising cross-bars having slots, and foot-rests which are alternately elevated and depressed by movements of the frame, two rock-shafts journaled in bearings in the seat-frame and each having two arms engaged with the slots in the cross-bars of the seat-frame, and two seat-inclining cams, a reversible seat-back, parallel links jointed to the back and rigidly attached to the rock-shafts, and seat-supporting slides engaged with the said cams and having inclines guided by the inclines on the seat-frame, the arms and cams of one rock-shaft being so arranged relatively to the arms and cams of the other rock-shaft that when the back is reversed the arms and cams of one shaft are depressed, while the arms and cams of the other shaft are raised, whereby a reversal of the position of the back causes a reversal of the position of the foot-rest frame and of the seat, as set forth.

3. In a car-seat, a fixed seat-frame having seat-guiding inclines, a reversible foot-rest frame below the seat and comprising parallel foot-rests and cross-bars connecting the ends of the rests, two rock-shafts journaled in the

seat-frame and having rigidly-attached cams, seat-supporting slides having inclines guided by the inclines on the seat-frame and having lugs bearing on said cams, a reversible back, parallel links jointed to the back and rigidly attached to the rock-shafts, and connections between the rock-shafts and the foot-rest frame, whereby a reversal of the position of the back causes also a reversal of the position of the foot-rest frame, the cams on one rock-shaft being so arranged relatively to the cams on the other rock-shaft that a reversal of the position of the back causes also a reversal of the position of the seat.

4. In a car-seat, a fixed seat-frame, two rock-shafts journaled in the seat-frame and having rigidly-attached cams, seat-supporting slides having inclines guided by corresponding inclines on the seat-frame and having lugs bearing on said cams, a reversible back, and parallel links jointed to the back and rigidly attached to the rock-shafts, the cams on one rock-shaft being so arranged relatively to the cams on the other rock-shaft that a reversal of the position of the back raises the cams on one rock-shaft and depresses the cams on the other rock-shaft, thereby reversing the position of the seat.

In testimony whereof I have affixed my signature in presence of two witnesses.

THOS. B. CANN.
